CLAIM

I claim the ornamental design for the beverage sleeve with pockets, as shown and described.

DESCRIPTION

FIG. 1 is a perspective view of a beverage sleeve with pockets in accordance with the present design;

FIG. 2 is a front view of the beverage sleeve with pockets shown in FIG. 1;

FIG. 3 is a right side view of the beverage sleeve with pockets shown in FIG. 1;

FIG. 4 is a back view of the beverage sleeve with pockets shown in FIG. 1; and,

FIG. 5 is a left side view of the beverage sleeve with pockets shown in FIG. 1.

The broken lines in the drawings depict environmental subject matter only and form no part of the claimed design.
